UNITED STATES PATENT OFFICE.

SYLVANUS EDWARD ROBINSON, OF BUFFALO, NEW YORK.

WATER-REGULATING DEVICE FOR BATH-TUBS.

SPECIFICATION forming part of Letters Patent No. 767,662, dated August 16, 1904.

Application filed September 4, 1902. Serial No. 122,135. (No model.)

To all whom it may concern:

Be it known that I, SYLVANUS EDWARD ROBINSON, a citizen of the United States, residing in Buffalo, in the county of Erie and 5 State of New York, have invented a new and useful Device for Bath-Tubs, of which the following is a specification.

My invention relates to improvements in bath-tub attachments, and has for its object 10 to provide an attachment whereby with great facility water may be discharged directly into the bath-tub or may at the election of the user be discharged into a hose or spraying device.

15 To attain the object stated, the invention consists in a bath-tub attachment constructed as hereinafter described and claimed, reference being had to the accompanying drawings, in which—

20 Figure 1 is a vertical sectional view of an attachment embodying my invention. Fig. 2 is a similar view of a slightly-different form thereof, and Fig. 3 is a plan view of an element of the attachment.

25 In the said drawings the reference-letter A designates a hollow cap provided with a screw-threaded entrance-opening b, adapted to be connected with the intake of a supply-pipe, (not shown,) whereby said hollow cap is operatively connected with the supply-pipe to receive the discharge thereof.

The reference-letter d designates an outlet formed in the periphery of the hollow cap A and disposed to direct the water downwardly 35 into the bath-tub, and the attachment will be used in this manner when it is intended to fill the bath-tub with water, as distinguished from discharging water into a spraying device.

40 The cap A is provided with a circular flange e, extending beyond the periphery of the cap proper and screw-threaded, as at e', on its edge. An auxiliary hollow cap H, adapted and intended for use in connection with a hose

45 and spray device, is screw-threaded at its attaching end to engage with the screw-threaded flange of the cap A. This cap H is provided centrally with a nozzle K, formed and adapted for connection with a hose, (not shown,) so that when the cap H is attached to the flange of the cap A the water instead of being discharged into the bath-tub through

the peripheral opening d will pass through the passage W between the caps and through the nozzle K into the hose, from which it 55 may be sprayed in the form of a shower, whereby the user may have a shower-bath.

It will thus be seen that with great facility by reason of the novel and simple construction and arrangement and interrelation of 60 parts composing my invention a user may discharge the water directly into the bath-tub for a plunge or other similar bath or may, by connecting the hollow cap H with the cap A and attaching the hose and spraying device 65 to the nozzle thereof have a shower-bath.

In Fig. 2 of the drawings a slightly-different form of the invention is shown wherein the circular flange e, Fig. 1, is continued into the circularly-disposed flange h, provided 70 with screw-threads i, adapted to have screw-threaded engagement with the cap H. The mode of operation and manner of utilizing this slightly-different form are the same as in the case of the form hereinbefore described, 75

Having thus described my invention, what I claim is—

1. In a bath-tub attachment, a hollow cap having an outlet in its periphery and a circular flange extending outwardly a distance approximately equal to the height of said hollow cap, and a second hollow cap having a nozzle, said second hollow cap being screwed upon the circular flange of said first-mentioned cap. 85

2. In a bath-tub attachment, a hollow cap having an outlet in its periphery and a circular flange extending beyond the periphery of the cap, and screw-threaded on its end, said hollow cap being provided on its rear side 90 with a threaded perforation for attaching the cap to the intake of a bath-tub and a second hollow cap interiorly threaded for attachment to said threaded flange and provided centrally with a nozzle, substantially as described. 95

In testimony whereof I have signed my name to this specification in the presence of two subscribing witnesses.

SYLVANUS EDWARD ROBINSON.
